UNITED STATES PATENT OFFICE.

HERBERT JACOB WILLIAM MORGENTHALER, OF BROOKLYN, NEW YORK.

IDENTIFICATION DEVICE.

1,371,925.

Specification of Letters Patent. Patented Mar. 15, 1921.

Application filed March 15, 1920. Serial No. 366,027.

To all whom it may concern:

Be it known that I, HERBERT J. W. MORGENTHALER, a citizen of the United States, and a resident of the city of New York, borough of Brooklyn, in the county of Kings and State of New York, have invented a new and Improved Identification Device, of which the following is a full, clear, and exact description.

10 This invention relates to improvements in identification devices, and more particularly to devices for identifying babies in hospitals and the like.

15 A further object is to provide an identification device which can be readily assembled to indicate the name of the child, and which can be quickly and easily positioned around the neck or arm of the child and sealed so as to prevent possibility of mis-
20 take.

With these and other objects in view the invention consists in certain novel features of construction, and combinations and arrangements of parts, as will be more fully 25 hereinafter described and pointed out in the claims.

In the accompanying drawings—

Figure 1 is a perspective view illustrating my improved identification device in use;
30 Fig. 2 is a plan view of the identification device detached;

Fig. 3 is an enlarged perspective view of one of the lettered beads; and

Fig. 4 is an enlarged view in transverse 35 section on the line 4—4 of Fig. 2.

My improved identification device comprises a series of beads 1 containing preferably letters so that the assemblage of these beads on a string or wire 2 will spell the 40 name of the child, the initials of the mother, or any other word or combination of letters which will positively identify the child.

On the string or wire 2 I provide a series of spacing beads 3 and where the lettered 45 beads 1 are used to spell out two names or the initials of a person, a spacing bead 3 will be located between the names or the initials.

The ends of the wire 2 are knotted or 50 twisted, as shown at 4, and are firmly and permanently connected by means of a seal 5 which is preferably of lead or soft metal so as to render it impossible of accidental loss or disconnection.

55 In maternity hospitals it is sometimes difficult to identify babies and it is always more

or less a source of worry to mothers to be sure that they have their own child. With my improved identification device, the possibility of error in identification is rendered 60 absolutely impossible. When the child is born, the identification device is placed around the arm or neck of the child and sealed as above indicated, and remains on the child until the mother takes the baby 65 away with her from the hospital and becomes a souvenir or heirloom.

By the provision of the lettered beads 1 any name or initials can be positioned on the cord or wire 2 and this is, of course, done 70 in readiness and prepared before the birth of a child so that it is ready for instant use and the mother can have any name on the identification device that she desires.

It is, of course, to be understood that the 75 beads are all perforated, as indicated at 6, for the reception of the wire or cord 2 and they may be variously shaped and variously made so as to permit their assemblage and permanent connection, and the device, when 80 complete, will constitute a necklace, or a bracelet, and absolutely prevent possibility of a mix-up of the children in the hospital.

It is, of course, to be understood that the letters or characters may be on both sides 85 of the beads so that they will appear regardless of how the beads are turned.

Various slight changes might be made in the general form and arrangement of parts described without departing from the invention, and hence I do not limit myself to the precise details set forth, but consider myself at liberty to make such changes and alterations as fairly fall within the spirit and scope of the appended claims. 95

I claim:

1. As a new article of manufacture, an identification device for infants comprising a flexible member, a series of perforated beads on the flexible member, said beads 100 having characters thereon, spacing beads on the flexible member maintaining the character beads in proper relation to each other, and a seal confining the ends of the flexible member. 105

2. As a new article of manufacture, an identification device for infants of the character described, comprising a string, spacing beads on the string, letter-containing beads on the string arranged to spell a name, the 110 ends of the string secured together, and a seal connecting the ends of the string.

3. As a new article of manufacture, an identification device for infants comprising a flexible member, lettered beads on the flexible member arranged to spell a name, spacing 5 beads on the flexible member, a seal confining the ends of said flexible member forming a necklace and locking said ends together.

4. As a new article of manufacture, an

identification device for infants, consisting of a cord, a series of spacing beads on the 10 cord, a series of lettered beads on the cord arranged together to spell a name, and a seal joining the ends of the cord, preventing the removal of the device or the disarrangement of the beads.

HERBERT JACOB WILLIAM MORGENTHALER.
